UNITED STATES PATENT OFFICE

172,137

AUTOMOBILE COMPASS OR THE LIKE

Ernest Franklin, Culver City, Calif., assignor of
one-half to Samuel Franklin, Culver City,
Calif.

Application June 26, 1953, Serial No. 25,676

Term of patent 14 years

(Cl. D42—7)

To all whom it may concern:

Be it known that I, Ernest Franklin, a citizen of the United States of America, residing at Culver City, in the county of Los Angeles, State of California, have invented a new, original, and ornamental Design for an Automobile Compass or the like, of which the following is a specification, reference being had to the accompanying drawing, forming a part hereof.

Figure 1 is a perspective view of an automobile compass embodying my new design;

Figure 2 is a front elevational view of the compass;

Figure 3 is a side elevational view of the compass; and

Figure 4 is a top plan view of the compass.

I claim:

The ornamental design for an automobile compass or the like, substantially as shown.
